United States Patent Office

Des. 232,625

Patented Sept. 3, 1974

232,625

STORAGE CART

Frank L. Shiflet, Waynesboro, Va., assignor to Hopeman Brothers, Inc., New York, N.Y.

Filed Mar. 16, 1973, Ser. No. 342,075

Term of patent 14 years

Int. Cl. D12—02

U.S. Cl. D12—25

FIG. 1.

FIG. 3.

FIG. 2.

FIG. 5.

FIG. 6.

FIG. 7.

FIG. 1 is a perspective view of a storage cart showing my design;

FIG. 2 is a top plan view thereof;

FIG. 3 is a bottom plan view thereof;

FIG. 4 is a left side elevational view thereof;

FIG. 5 is a right side elevational view thereof;

FIG. 6 is a front elevational view thereof; and

FIG. 7 is a rear elevational view thereof.

I claim:

The ornamental design for a storage cart, as shown.
